HIRAM J. CARSON, OF CEDAR RAPIDS, IOWA

SHUT-OFF COCK

Application filed May 9, 1927. Serial No. 189,943.

This invention relates to shut-off valves and cocks in relatively inaccessible locations, and for underground pipes used for the distribution of liquids and gases, and more particularly gas service pipes leading into buildings.

In the distribution of liquids and gases, more particularly illuminating gas, it is usual to provide the service pipe leading from the street main into a building with an underground stop-cock, to be closed only in emergencies. In practice the emergency requiring such closure may happen at any time, and on the other hand may not occur for a dozen years, or at all. When the occasion does arise, as in case of a fire, for example, it is highly necessary to shut off the gas from the service pipe. It is often found, however, that after a long lapse of time the stopcock has become stuck in open position and cannot be closed.

This action is common to stop-cocks now in general use, and frequently requires the digging up and loosening of the stop-cock plug before it can be turned. Gate-valves are often used for this service, but are expensive, and necessitate the location of the valve stuffing-box below ground. In case leakage occurs at the stuffing-box it becomes necessary to dig down to the valve to permit the re-packing of the stuffing-box.

This invention consists of an improvement in what are known as mine-cocks, in which the large end of a tapered plug is below, with a spring to hold it in place. In its present form it is not adapted for underground use because when once turned it is not likely to seat tightly, and seepage or leakage around the top of the plug results.

The object of this invention is to provide a simple, inexpensive shut-off cock which may at any time be operated with certainty, and so constructed as to prevent the escape of gas by leakage or seepage whether the cock be open or closed.

In the accompanying drawing, forming a part of this specification a stop-cock embodying the invention is shown in a single figure, the most of the parts being shown in section in a plane central and vertical to the structure as installed for use. It is to be understood

that the parts above the valve proper are much reduced in height, as indicated by the lines of breakage therein.

In the drawing, the numeral 5 denotes a service-pipe, as for gas. This is commonly disposed in a horizontal position underground, and is provided with a shut-off cock of some kind. The cock herein shown is of the mine-cock type, as above mentioned, and comprises the main body 6, a tapered plug 7 seated therein, with its larger end downward, a closure cap 8 below the plug, and a spring 9 disposed between the plug and the cap, and adapted to press the plug more or less firmly into its seat. The smaller, upper end of the plug is provided with an angular shank or stem 10 (usually square) whereby the plug may be turned with a wrench or other suitable appliance. Provision being made to give access to the plug-shank from above ground, as by a well or casing 11, this valve is turnable from above by a socket-wrench 12. In the event of its sticking in an open position, as will generally happen in the case of long continued service in that position, the plug may be loosened by rapping on the upper end of the wrench, or by a short jarring movement of the wrench itself. In such a case, however, the act of loosening and turning the plug is apt to dislodge fine particles of dust or rust into the space between the plug and its seat and cause a slight, but permanent leakage around the upper end of the plug. This would call for the expensive operation of digging down to the valve to get access to it, and sometimes the removal of the valve from the service pipe in order to reseat the plug.

An improvement which eliminates all this trouble and expense is herein shown, and is described as follows:

On one side of the valve body, surrounding the plug-shank, is formed an annular hub 13, which is threaded to receive the threaded end of a stand-pipe 14. The upper end of the stand-pipe is also threaded, and is provided with a cap 15 whereby it is hermetically sealed. The interior of the pipe is of a suitable size to admit the head of a socket-wrench when the cap is removed. By means of the wrench the valve-plug is easily loosened, if

stuck, and turned to shut off the service gas, in the case of an emergency such as above mentioned. If now the valve should leak a little, whether in open or closed position, the 5 replacement of the cap effectually shuts off its escape, and there is no loss and no need to reseat the valve.

The main purpose of the casing or housing 11 is to permit a little movement of the stand- 10 pipe according to contraction and expansion of the service pipe, or the main to which it connects, (not herein shown). This is more especially important under conditions in 15 which the underground piping is subjected to extremes of temperature. In other cases the housing may be dispensed with.

It is to be understood that the stand-pipe extends to the surface of the ground, or near it, and that normally the cap is affixed, as indicated by the dotted outline. As thus constructed the improved cock for underground pipes constitutes an easily operated and bot- 20 tle-tight shut-off.

To give effect to the jarring movement of 25 the wrench, as above referred to the wrench should abut on the plug in such manner as to force it downwardly by such jar or thrust. This is shown herein as a shank which is longer than the depth of the wrench socket, so that 30 a blow or thrust of the wrench bears on the end of the shank.

Having thus described my invention, I 35 claim:

1. A normally sealed shut-off cock structure for underground gas pipes comprising: 40 a pipe connecting body adapted to be connected in the underground pipe line, said body having a tapered valve seat therein with the larger end of the seat opening downward; 45 a correspondingly tapered plug within and cooperable with said seat, said plug being adapted for rotation and also downward end- 50 wise movement relative to said seat and provided at its upper portion with an upwardly facing portion and formed to cooperate with a wrench for turning; means for sealing the 55 plug opening at the underside of the connecting body; means within the connecting body normally urging said plug upwardly into the seat; a pipe having a sealed connection at its lower end with said pipe connecting body and extended upwardly to a point readily 60 accessible from the ground level; and removable sealing closure means for the upper end 65 of said pipe whereby said closure means may be temporarily removed to receive a wrench insertable within the pipe to engage and turn the plug and also to engage said upwardly facing portion of the plug to force the latter 70 downward within the tapered seat to sufficiently loosen the plug to permit turning.

2. A sealed shut-off cock structure comprising: a pipe connecting body adapted to be connected in the underground pipe line, said body having a valve seat therein and a pipe

attaching section on its upper side; an aper- 70 tured plug in said seat, said plug being adapt- 75 ed for both rotation and endwise movement relative to said seat, said plug being provided at its upper portion with an upwardly facing portion and formed to cooperate with a cor- 80 responding wrench formation; means for sealing the plug opening at the underside of the body; a pipe having a sealed connection at its lower end with said pipe-attaching sec- 85 tion and extending upwardly to a point read- 90 ily accessible from the ground level; and re- 95 movable sealing closure means for the upper end of said pipe whereby said closure means may be temporarily removed to receive a wrench insertable within the pipe to engage the corresponding plug wrench formation to turn the latter and the wrench also utilized by downward endwise movement to engage said upwardly facing portion of the plug to force the latter downward to loosen the same rela- 95 tive to its seat.

In testimony whereof I affix my signature.
